Primary Examiner — Bridget L Eland(74) *Attorney, Agent, or Firm* — Cantor Colburn LLP(57) **CLAIM**

The ornamental design for a cover for data relay device, as shown and described.

DESCRIPTION

FIG. 1 is a perspective view of a cover for data relay device, showing my new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken line shows portions of a cover for data relay device which form no part of the claimed design.
